UNITED STATES PATENT OFFICE.

JULIAN WEST AND EDWARD C. CAMPBELL, OF NORFOLK, VIRGINIA.

ATTACHMENT TO REFRIGERATING APPARATUS.

1,427,041.

Specification of Letters Patent. Patented Aug. 22, 1922.

Application filed December 20, 1921. Serial No. 523,740.

To all whom it may concern:

Be it known that we, JULIAN WEST and EDWARD C. CAMPBELL, citizens of the United States, residing at Norfolk, in the county of 5 Norfolk and State of Virginia, have invented certain new and useful Improvements in Attachments to Refrigerating Apparatus, of which the following is a specification.

This invention relates to attachments for 10 refrigerating apparatus, and has for one of its objects to provide a simply constructed attachment whereby the low temperature of the water drained from the ice is utilized to decrease the temperature in the food containing chamber.

Another object of the invention is to provide a device of this character which may be installed in refrigerating apparatus of varying sizes and constructions, and without 20 material change in the attachment or in the refrigerator.

With these and other objects in view, the invention consists in certain novel features of construction as herein shown and described and then specifically pointed out in 25 the claims, and in the drawings illustrative of the preferred embodiment of the invention:—

Figure 1 is a vertical section of a conventional refrigerator with the improved attachment installed therein.

Fig. 2 is a transverse section on the line 2—2 of Fig. 1.

Fig. 3 is a plan view of one unit of the improved attachment.

Fig. 4 is a vertical section on the line 4—4 of Fig. 3.

Fig. 5 is a vertical sectional elevation of the complete device.

Fig. 6 is a horizontal section of the lower unit of the improved device.

Fig. 7 is a section on the line 7—7 of Fig. 6 of the lower unit.

Figure 8 is a bottom plan view of a part 45 of the structure shown in Figure 5.

The improved device is designed to be installed in the food chamber of a refrigerator to receive the cold drainage water from the ice chamber and through which the low temperature of the water is permitted to slowly pass to permit the cold from the water to enter the food chamber and thus supplement the cold from the ice in the ice chamber.

The improved device is in two coacting

units, an upper vertical unit located at the 55 rear of the food chamber and into which the drainage from the ice chamber leads, and a horizontal unit disposed upon the floor of the food chamber and into which the drainage from the upper unit leads, and from which 60 the final drainage leads to the waste pan or the like.

The upper or vertical unit is in the form of a relatively thin oblong casing represented as a whole at 10 and having an inlet 11 65 in the top or upper side and an outlet 12 in the bottom or lower side.

A vent 13 is also disposed in the top and a "draw off" 14 in the bottom of the casing, the latter having a water tight closure cap 15.

Disposed within the casing 10 are a plurality of vertical and transverse partition or baffle members to cause the water entering by the intake 11 to take a vertically zig zag or circuitous course to the outlet 12, as indicated 75 by the arrows in Fig. 4.

The drainage water falling through the intake 11 falls upon an inclined partition 16 and flows thence between a vertical partition 17 and one end wall of the casing. The partition 17 stops short of the bottom of the casing so that the water can rise between the partition 17 and the next partition 18, which stops short of the inclined partition 16 and the next vertical partition 19. A fourth vertical partition 20 extends between the side walls of the casing and intermediate the space between the partition 19 and the adjacent end wall of the casing and stops short of the top of the casing and is connected at 90 its lower end to one end of a second inclined partition 21, the latter connected at the other end to the partition 18 and spaced from the bottom of the casing.

The water will thus flow in a continuous 95 vertically zig zag or circuitous course through the casing and is thus held for a greater length of time within the casing.

The intake 11 and the outlet 12 of the vertical unit are provided respectively with wire 100 cloth screens, indicated at 22 and 23 to prevent the entrance of foreign matter.

The lower or horizontal unit comprises a flat oblong casing represented as a whole at 24 and having a plurality of internal partitions 25 attached to the walls of the casing 24 having openings and passages 26 at their alternate ends, so that water flowing through

the lower unit is caused to take a zig zag or circuitous course, as indicated by the arrows in Fig. 6.

Fitting over the outlet 12 of the upper casing or unit 10, is a vertical branch 27 of an obliquely directed or inclined conductor 27', the latter leading at 28 into the casing 24 at one end.

Leading at 29 into the casing 24 at the 10 other end, is an inclined conductor 30 with a downwardly directed outlet 31 at its lower end, the discharge 31 being preferably in vertical alinement with the outlet 12 of the upper unit and the intake 27 of the upper 15 unit.

By this arrangement the improved device may be installed in the ordinary refrigerator in place of the usual drainage tube and requires no change whatever in 20 the refrigerating structure.

The walls of the refrigerator are represented at 32, the ice chamber at 33 and the food chamber at 34, and it will be obvious that when the improved apparatus is 25 installed therein, the cold water drained from the ice will pass slowly through the two units and accumulate therein until the compartments produced by the transverse partitions are "flooded". After this the water 30 will escape through the outlet 31 only so fast as it is replenished from the melting ice.

The two units will thus be constantly supplied with water almost ice cold and the cold therefrom distributed uniformly 35 within the food chamber and materially decreasing the temperature of the same.

Thus a material decrease of temperature is attained in the food chamber with the same amount of ice, or the same temperature 40 heretofore attained in the ordinary construction of refrigerator with a reduced quantity of ice.

The improved device will be constructed wholly of sheet metal, preferably galvanized or otherwise rendered non-corrosive, 45 and of any size or form to fit various forms of refrigerators.

The improved apparatus may be applied without material structural change to other 50 than refrigerators, for instance in cold storage plants or of any structure wherein ice is used as a refrigerant.

The preferred embodiment of the invention 55 is disclosed in the drawings and set forth in the specification, but it will be understood that modifications within the scope of the claimed invention may be made in the construction without departing from the principle of the invention or sacrificing any 60 of its advantages.

Having thus described the invention, what is claimed as new is:—

1. An attachment for a refrigerating apparatus comprising a vertically disposed drip receiver having an intake at the upper 65 side and an outlet at the lower side, a horizontally disposed drip receiver having internal vertical division members dividing the interior into a plurality of compartments side by side with communicating 70 passages at their alternate ends, one of the terminal compartments having an intake and the other terminal compartment having an outlet, an inclined conductor between the outlet of the vertical drip receiver and the 75 intake of the horizontal drip receiver, and an inclined conductor leading from the outlet of the horizontal drip receiver.

2. An attachment for a refrigerating apparatus comprising a vertically disposed drip receiver having an intake at the upper side and an outlet at the lower side, a horizontally disposed drip receiver having internal vertical division members dividing the interior into a plurality of compartments 85 side by side with communicating passages at their alternate ends, one of the terminal compartments having an intake and the other terminal compartment having an outlet, a conductor between the outlet of the 90 vertical drip receiver and the intake of the horizontal drip receiver, and a conductor leading from the outlet of the horizontal drip receiver.

3. The combination with a refrigerator 95 including an ice chamber having a discharge tube and a food chamber having a drainage tube, of a vertical drip receiver having an intake in the upper side communicating with the outlet of the ice chamber and an outlet in the lower side, a horizontal drip receiver supported on the bottom of the food chamber and having internal vertical division members dividing the interior into a plurality of compartments side by side with communicating 100 passages at their alternate ends, one of the terminal compartments having an intake and the other terminal compartment having an outlet, an inclined conductor between the outlet of the vertical drip receiver and the intake of the horizontal drip receiver, and an inclined conductor between the outlet of the horizontal drip receiver and the drainage tube leading from the food 110 chamber.

In testimony whereof, we affix our signatures hereto.

JULIAN WEST.
EDWARD C. CAMPBELL.
